UNITED STATES PATENT OFFICE

GEORGE E. McKEEN, OF MINNEAPOLIS, MINNESOTA

COMBINATION TIE AND COLLAR SUPPORT

Application filed March 28, 1932. Serial No. 601,588.

This invention relates to an improved device adapted for use in connection with a collar and a tie to hold the same in position upon the wearer.

5 An object of the invention is to provide a combination tie and collar support comprising a cross bar adapted to be fitted between the collar band and the tie knot and having legs provided with means adapted to engage the points or corners of a collar whereby said corners will be prevented from rolling upwardly and excessively spreading.

A further object is to provide a device of the class described comprising a cross bar, 15 and a pair of spaced resilient legs having means at their lower ends for engaging the points of the collar to secure the latter thereto, and recesses being provided at the junctures between said cross bar and said legs 23 adapted to receive the tie band, whereby the tie will be firmly held in place in the collar and the points of the collar will also be retained in proper position.

25 A further object is to provide an inexpensive combination tie and collar support constructed of a single strand of spring wire and having means for engaging the points of the collar, and other means for engaging the collar and tie bands, whereby the collar and tie may be retained in their proper places upon the wearer.

Other objects of the invention will appear from the following description and accompanying drawing and will be pointed out in 35 the annexed claims.

In the accompanying drawing, there has been disclosed a structure designed to carry out the various objects of the invention, but it is to be understood that the invention is 40 not confined to the exact features shown as various changes may be made within the scope of the claims which follow:

In the drawing:

45 Figure 1 is a view showing the device attached to a collar;

Figure 2 is a perspective view showing the device removed from the collar;

50 Figure 3 is an enlarged cross sectional view on the line 3-3 of Figure 1, showing the tie

band fitted into the recesses provided at the upper portion of the device; and

Figure 4 is an enlarged detail showing the means provided at the lower ends of the legs for engaging the collar.

In the selected embodiment of the invention here shown, for purposes of disclosure, there is illustrated in Figures 1 and 3, a collar 2 comprising the usual points or corners 3 and neck band 4. A tie 5 is shown in combination 60 with the collar and comprises the usual knot 6 and the tie band 7.

The novel device featured in this invention is best shown in Figure 2, and comprises a cross bar 8 which preferably is curved as 65 shown, and is provided at its ends with suitable recesses 9 and a pair of resilient legs 11. The device is made from a single strand of spring wire which is bent as shown in Fig. 2, so as to provide upstanding portions 12, each 70 of which defines a wall of one of the recesses 9. These recesses are adapted to receive the tie band 7, as shown in Figure 3.

The terminals 13 at the free ends of the legs 11 are sharpened whereby they may penetrate the material of the collar, as shown at 75 14 in Figure 3, so as to retain the device in proper position upon the collar. The end portions of the legs 11 are preferably bent so as to form loops 15, having their upper portions 16 substantially horizontally disposed as shown in Figure 4, so as to limit the penetration of the terminals 13.

In use, the device is attached to the collar as shown in Figure 1. To thus attach the device to the collar, the cross bar 8 is inserted between the collar band 4 and the tie band 7, as shown in Figure 3, whereby the portions 12 at the upper ends of the legs 11 will be positioned between the body 2 of the collar and 90 the tie band 7. The terminals 13 are then inserted into the material of the collar points 3, as shown at 14 in Figure 3. When the device is attached to the collar as above described, the tie knot 6 cannot slide downwardly out of place, and the points or corners 3 of the collar will always be held in their normal straight positions by the legs 11, as shown in Figure 1.

The points 13 are preferably inserted into 100

the usual seams provided at the edges of the collar, as shown in Figure 1, so as not to pierce the collar. When the legs are thus positioned, the device will be concealed by the wings of the collar and the tie so that it cannot be seen when in use. The cross bar 8 is shaped so that it may readily and quickly be inserted between the collar and tie bands, after which the terminals 13 of the leg 11 are engaged with the points of the collar, as shown in Figures 1 and 3. The recesses 9 provided at the upper portion of the device are very important in that they receive the tie band and cooperate to hold it in place in the upper fold of the collar, as shown in Figure 3, which makes it impossible for the tie to become disarranged. The extreme simplicity of the device is such that it may be manufactured at a very small cost, as compared to devices of this general character now in use.

I claim as my invention:

1. A combination tie and collar support formed from a single strand of wire and comprising a cross bar provided with legs extending downwardly therefrom, means at the ends of said legs for securing them to a soft collar adjacent the corners or points thereof, and said cross bar being provided at its ends with suitable recesses adapted to receive the lower edge of a neck tie band to thereby retain said band in position in the upper portion of the collar.

2. A combination tie and collar support formed from a single strand of wire and comprising a cross bar adapted to be fitted between a tie knot and the neck band of a collar or shirt, said cross bar having means at its ends adapted to receive the lower edge of a neck tie band, and said means comprising upstanding portions adapted to be fitted between the tie band and the body of the collar, and a pair of resilient legs extending downwardly and inwardly from said upstanding portions and having loops formed at their lower ends provided with terminal hooks adapted to engage the material of the collar, said means and said legs cooperating to retain the tie band in place in the upper portion of the collar and also to hold the depending corners or joints of the collar in proper place.

3. A combination tie and collar support comprising a cross bar adapted to be fitted between a tie band and the neck band of a collar or shirt, said cross bar being provided at its ends with downwardly, and outwardly, and upwardly bent portions cooperating to form U-shaped recesses adapted to receive the lower edge of a neck tie band, and said cross bar having downwardly extending resilient legs provided with terminal hooks adapted to engage the material of the collar adjacent to the lower corners or points thereof, whereby the collar points will be held in proper place and the tie band and knot will

also be retained in place in the upper portion of the collar.

4. A combination tie and collar support comprising a curved cross bar adapted to be fitted between a tie band and the neck band of a collar or shirt, said cross bar being provided at its ends with downwardly, and outwardly, and upwardly bent portions cooperating to form U-shaped recesses adapted to receive the lower edge of a neck tie band, said upwardly bent portions having resilient legs extending downwardly therefrom and provided with terminal hooks adapted to engage the material of the collar adjacent to the lower corners or points thereof, whereby the collar points will be held in proper place and the tie band and knot will also be retained in place in the upper portion of the collar, and means for limiting the penetration of said terminal hooks in the material of the collar.

In witness whereof, I have hereunto set my hand this 25 day of March, 1932.

GEORGE E. McKEEN.
